METALLIC CONTAINER

Louis M. La Duke, Jackson, Mich., assignor to
 Potter Manufacturing Company, Jackson,
 Mich.

Application August 27, 1930, Serial No. 477,999

5 Claims. (Cl. 190—28)

This invention relates to metallic containers, being particularly adapted to containers of the trunk type such as are secured to automobiles, usually at the rear thereof; although it will readily be seen that it might equally well be used upon containers of many other types.

An important object of my invention is the provision of such a trunk or other container having a lid which may easily be opened and closed in the usual manner, but which when closed will be moisture and dust proof, being tightly sealed at all points of juncture of the lid and body.

When a trunk of the type mentioned is to be used upon an automobile, it is of course important that seepage into it of moisture or dust be prevented as effectively as possible. In the past one of the principal sources of trouble in such trunks has been the difficulty of tightly sealing the meeting edges of lid and body at the hinges, or along the hinged side; for most such trunks have hinged lids. From standpoints of ruggedness, economy of production and ease of assembly, long piano hinges have usually been preferred for such purpose—but these obviously are especially difficult to seal in such fashion that when the trunk is closed, seepage through the many sliding joints and around the hinge pin will be prevented when the car carrying it is traversing a dusty road, or being washed with a hose, or in a driving rain.

It is therefore also an important object of my invention to provide such a container in which a long hinge may be used if desired, but in which the possibility of seepage through the hinge and hinged edges will be prevented by their unique configuration, and by the embodiment in protective relation thereto of a tight and effective seal.

Another object of my invention is the provision of such a seal along the hinged edge of a container of this type, wherein any water or other flowable matter which partially makes its way into the space adjoining the hinge will be drained away outside the container under the natural influence of gravity.

It is also an object of this invention to provide means for tightly and effectively sealing all of the other meeting edges of the lid and body of the trunk, so that when closed it is weather and dust-proof.

A further object of this invention is the incorporation in such a trunk having a hinged lid of means requiring the addition of no extra parts whatever, for limiting the backward movement of the lid, so that it may not be swung backwardly too far.

It will become apparent that this invention con-

cerns itself principally with means for insuring a tight seal between the lid and body of a trunk when the lid is closed and secured and in this respect it will be found to be an improvement upon my previous invention for which an application for patent was filed in the United States Patent Office, and which resulted in the issuance of Letters Patent numbered 1,767,143, on June 24, 1930.

A still further object of this invention is the incorporation therein of a hinge of improved design.

Other objects and advantages will be apparent from the following disclosure wherein reference is made to the accompanying drawing illustrating a preferred embodiment of my invention, and wherein similar reference numerals designate similar parts throughout the several views.

In the drawing:

Figure 1 is a vertical cross sectional view through a metallic automobile trunk embodying my invention, showing the lid closed and latched.

Figure 2 is an enlarged detail sectional view of the improved means I employ to seal the meeting edges of the body and lid of the trunk other than the hinged edge, showing adjoining fragmentary portions of the lid and body in closed relation, but not tightly drawn together.

Figure 3 is a view similar to Figure 2, but showing the meeting edges tightly drawn together, as by a lever latch.

Figure 4 is an enlarged detail sectional view of my improved hinge construction and associated sealing means for that edge of the trunk, showing also a portion of the lid to which they are attached, as ready for, but not yet attached to, the body of the trunk.

Figure 5 is a detail sectional view of the upper edge of the side of the body of the trunk to which the lid is to be hinged, being shown in such positional relation with respect to the lid and its associated parts as shown in Figure 4 that it is ready for attachment of the latter thereto by a mere downward movement of the lid portions.

Figure 6 is a perspective view showing fragmentarily the hinged edges of the body and lid of the trunk in assembled relation and secured together, the lid being thrown back to the stopped position.

Referring now to the drawing:

The numeral 10 designates the body of a trunk of which 11 indicates the lid. The lid may be hinged to the body of the trunk at its rear, as upon the pin 12, to enable it to be opened by lifting the front edge of the lid and swinging it back in the conventional manner. The hinged

links 13, which also may be of conventional form, may be utilized to prevent the danger of unwanted closing of the lid.

The lower edge of the lid 11, along its three free sides which are not hinged to the body of the trunk, are bent inwardly and backwardly upon themselves as best shown in Figures 2 and 3, a space being left between the remainder of the lid and the bent back portions, as there shown, the lowermost part, 14, of the bent back portion presenting a slanting face. The bent back portion constitutes in its entirety a resilient bead. Along the corresponding three sides the body of the trunk is bent inwardly and then again upwardly to form the substantially horizontal ledge or shelf, 15 for reception of the bead at the bottom edge of the lid. Preventing contact of the lid and the ledge is the interposed cushioning and sealing strip 16, contoured as shown in Figures 2 and 3, and longitudinally apertured as at 17, comprising essentially a rubber tube 31 having right-angularly projecting arms 32 and 33—the former horizontal and the latter vertical. The outer surfaces of the projecting arms, which are in the form of strips of rubber, are tangential to the tube, and present substantially flat outer surfaces disposed right angularly to each other, enabling the strip to be set in and upon the ledge in the manner shown in Figures 2 and 3, with the vertical projecting arm bearing against the inset vertical wall 35 which rises integrally from the inner extremity of the shelf 15. This construction will be seen to be somewhat similar to that disclosed in my aforementioned previously issued patent, but the formation of the resilient sealing strip will be noticed to be an improvement thereover, as the aperture 17 permits use of a more resilient strip which is subject to greater deformation, and consequently produced a more effective seal. My preferred method of securing the strip in the ledge 15 is clearly shown in Figures 1 and 2, comprising teats, such as 18, struck out from the metal of the body of the trunk and bent down to secure the strip, as there shown.

The lower rear or hinged edge of the lid is bent inwardly as at 19, (Figures 4 and 6) for a purpose which will become apparent. The corresponding part of the body of the trunk is formed with a cooperating ledge 25, (Figures 5 and 6), similar to the ledge 15 which is formed around the other three edges of the body, excepting that rather than being horizontal, it slopes downwardly, as shown in Figures 1, 5, and 6, to allow water to drain away and down the outside of the trunk. Secured to the lid of the trunk directly above the inbent edge 19 is a hinge comprising two elongated flaps, 20 and 21. Of these, the flap 21 is a flat strip of the kind commonly used upon piano-type hinges and is firmly secured to the lid of the trunk in any suitable fashion, as by spot welding, while the flap 20 is of a special configuration which is best shown in cross section in Figure 4, and serves as the attaching medium for secural to the body of the trunk. The two flaps are hingedly joined in conventional fashion by the pin 12. Figure 4 shows the relative position which the hinge, lid, and associated parts, assume when the lid is closed upon the body of the trunk, and it will be seen that the formation of the flap 20 of the hinge is such that when in that position, immediately after leaving the pin 12, it is bent away from the opposite flap 21, in the manner shown in Figure 4, producing the sloping surface 22. It then rises vertically a spaced dis-

tance from the other flap and the lid; this vertical portion being indicated by the reference character 20, which is also the general designation of that flap of the hinge. It is then bent back upon itself and away from the other flap as at 23, the bent back portion 23 being parallel to and spaced from the other vertical portion 20 by a distance approximately equal to or slightly less than the thickness of the metal of which the body of the trunk is formed, thereby producing the elongated slot 26.

The extremity of the flap 20 of the hinge is thus formed as an elongated and downwardly opening clip, which, as it is slightly shorter than the inside of the back of the trunk, may be secured to the top thereof by forcing it over the upstanding edge 24, (Figures 5 and 6). Figures 4 and 5 show these parts in detail section, before assembly, and in proper positional relation, so that if Figure 4 were moved downwardly upon Figure 5 in the direction indicated by the arrow in Figure 4, the straight upstanding edge 24 of the back of the trunk might be forced into the slot 26, to be frictionally held by the resilient parallel sides 20—23. Figure 6 shows the assembly of these parts in perspective after being secured together, and after they have been adjusted to the desired position they may be firmly fixed therein by striking or partially punching out the metal as shown at 27. While assembling these parts it will be seen that it is a simple matter to adjust the relative position in which the lid is secured to the trunk by merely tapping with a hammer before the punches 27 are made; as the clip formed by the flap 20 of the hinge may in that manner be slid in any desired direction upon the vertical edge 24 of the trunk body.

It will be seen that by the very formation of my improved hinge construction the possibility of water, dust, or other foreign matter working up through it and into the interior of the trunk is practically eliminated; but to render the closure even more secure, and effect practically a hermetic sealing thereof, I preferably insert the resilient sealing member 30, which may be in the form of a rubber tube, between the two flaps of the hinge and running the length of the back of the trunk. This, when the lid is closed, is compressed between the two flaps of the hinge above the butt, as shown in Figure 4, thus tightly sealing the only possible remaining ingress, as the other three sides are sealed by the strips 16. The position the rubber tube 30 assumes when the lid is opened is shown in Figure 6.

Figure 6 also shows the additional stop which the inbent lower back edge 19 of the lid furnishes, to limit the rearward movement of the lid when it is thrown back. As there shown the portion 19 engages against the sloping surface 22 of the flap 20 of the hinge when the limit of its movement is reached.

If suitable clamping latches 28, Figure 1, are provided to firmly draw the lid downwardly upon the body of the trunk, compressed rubber then seals all meeting edges of the lid and body of the trunk, the hinged as well as the unhinged sides, acting as a gasket to tightly seal all possible leakage spaces between the cover and the trunk.

While it will be apparent that the illustrated embodiment of my invention herein disclosed is well calculated to adequately fulfill the objects and advantages primarily stated, it is to be understood that the invention is susceptible to variation, modification and change within the spirit and scope of the subjoined claims.

I claim:

1. In a container having a hinged lid, means for hingedly affixing the lid to the container and simultaneously preventing ingress of foreign matter into the container through the hinge, comprising a sloping ledge carried by and adjacent and substantially parallel to the top of the hinged side of the container, said ledge slanting downwardly toward the exterior of the container, a substantially vertical inset wall rising from the inner extremity of the ledge, a lid for pivotal affixture to the container in a position in which its hinged extremity extends downwardly adjacent to and outside the inset wall, a hinge pin supported by the lid near the lower extremity of the hinged edge thereof, and a hinge plate rotatable about the pin and affixable to the inset wall above the normal line of the pin.
2. In a container having a hinged lid, means for hingedly affixing the lid to the container and simultaneously preventing ingress of foreign matter into the container through the hinge, comprising a sloping ledge carried by and adjacent and substantially parallel to the top of the hinged side of the container, said ledge slanting downwardly toward the exterior of the container, a substantially vertical inset wall rising from the inner extremity of the ledge, a lid for pivotal affixture to the container in a position in which its hinged extremity extends downwardly adjacent to and outside the inset wall, a hinge pin supported by the lid near the lower extremity of the hinged edge thereof, a hinge plate rotatable about the pin and affixable to the inset wall above the normal line of the pin, and an elongated resilient member positioned between the pintle and the interior of the container, and compressible upon closure of the lid.
3. In a container having a hinged lid, a body portion having an inset upper wall forming a ledge near its stop, an elongated hinge having a pintle extending along one side of the container and arranged near the bottom of said inset wall and directly above the ledge, the lid having a portion extending down over the ledge alongside but spaced from the inset wall and in alignment with the body portion below the ledge, the hinge having one flap secured to said lid portion and another to the body portion, and an elongated resilient sealing member located above the hinge pintle and between said inset wall and downwardly projecting lid portion and compressible 10 upon closing the lid.
4. In combination with a metallic container having upstanding walls and an open top, a cover for the open top formed to extend over and part way down outside said walls, and means for hingedly affixing the cover to the container and simultaneously preventing ingress of foreign matter into the container at the hinged edge, comprising a hinge plate carried by the cover, another hinge plate affixed to the outside of one 15 of said walls of the container with its butt edge below the top thereof, a hinge pin pivotally connecting said hinge plates along a line spaced below the top of said wall, and resilient sealing means arranged between the plates and compressible 20 thereby upon closing of the cover.
5. In combination with a container having upright walls and an open top, a lid hinged to the outside of one of said walls below the top of the wall and arranged to close said open 25 top and having a portion partially overlapping the wall on the hinged side, a hinge pivotally securing the lid to the container on said side and comprising flaps secured to the overlapping portions of the lid and body, a pintle connecting 30 the flaps and spaced below the top of the wall, and means for sealing the hinged edge comprising an elongated resilient member positioned between the flap secured to the cover and the wall and compressible between the same upon 35 closure of the lid.

LOUIS M. LA DUKE.
